INVENTOR

UNITED STATES PATENT OFFICE.

RICHARD A. BREUL, OF BRIDGEPORT, CONNECTICUT.

DOORKNOB.

1,341,969.

Specification of Letters Patent.

Patented June 1, 1920.

Application filed October 9, 1919. Serial No. 329,463.

To all whom it may concern:

Be it known that I, RICHARD A. BREUL, a citizen of the United States of America, and a resident of Bridgeport, county of 5 Fairfield, and State of Connecticut, have invented a certain new and useful Improvement in Doorknobs, of which the following is a specification.

My invention relates to knobs used in connection with door locks, for the operation of the latch bolts therein, and while it is useful, practicable, and preferable for the manufacture of such knobs provided with china, composition, or metal head portions, 15 is specially designed and adapted for the construction of such knobs having head portions made of transparent or tinted glass.

It is the main object of my invention to construct such door knobs in a manner by 20 which a more preferable, neat, smooth, strong, and reliable article may be produced at a smaller expense than present makes, to provide them with a safeguard against danger of breakage by shock or concussion, 25 to add to its appearance by the introduction of reflective material, and also by special shaping of the knob base, applied in a manner to be of constructive service.

The principles of my improvement are 30 illustrated in the drawings, in which:—

Figure 1 shows a side view of a completed knob according to my invention, and Fig. 2 represents a like view of the knob I use therein. Fig. 3 is a side view of the 35 knob holding ferrule, and Fig. 4 a sectional view of Fig. 2 below line α . Fig. 5 represents a side view of the body portion contained within the ferrule, Fig. 6 a bottom view thereof, and Fig. 7 is a plain disk 40 of packing material.

Referring to the drawings, in which similar characters refer to similar parts throughout the several views, I hereby proceed to describe my invention:

As shown complete in Fig. 1 of the drawings and the various parts in detail in the other drawings, my improved door knob consists of a sheet metal cup or ferrule b , a steel or cast metal body part, C , firmly 50 contained within the central portion b'' and lower end b'''' of ferrule b , and the glass knob a , held in and by the upper portion of the ferrule b as hereafter described.

By various suitable press or cupping operations a sheet metal blank is formed and drawn to the shape of ferrule b , Fig. 3, and

arranged to receive a hollow spindle bushing or cylindrical body, c , shaped as shown in Figs. 5 and 6, to have a body portion c' with a toothed or knurled surface, c'' , a reduced lower part, c''' , and containing an aperture d , therethrough, of a shape and size conforming to the lock spindle, to which it is to be attached. Said knurled body portion c' is of proper size to be rigidly held 65 within the central portion b'' of ferrule b , when forced thereinto by pressure, and to strike and rest against the bottom thereof, the aperture d' therein conforming to and alining with d , in and through bushing c . 70

The upper surface portion of base a' of the knob head up to its conjunction with the neck portion (see Fig. 2) is provided with an annular row of shallow grooves, a'''' , arranged in scallop formation, and 75 alining therewith, a like row of similar grooves, a''''' , encircles the adjoining surface of the knob neck. The upper part, b' , of the ferrule b is of proper size to admit and inclose knob base a' , and its rim portion 80 is formed by a row of lobe shaped teeth, b'' , coinciding in shape and number with the row of grooves a'''' described above. These teeth, (see Fig. 3), are formed with considerable spacing between them, to allow 85 them to be bent inwardly at right angles over the rounding edge of the knob base a' contained in the ferrule cup b' , and the ends of the teeth are furthermore sufficiently reduced in width, so as to enter into 90 the recesses or grooves of row a'''' , to rest against the bottom and sides of each groove in order to prevent any loose action or movement of the knob head within such fastening. These features are properly 95 illustrated in the sectional view represented in Fig. 4, the shape and arrangement of the grooves being shown at one side thereof, while those on the other side are covered by the inwardly bent teeth of part of 100 row b'' of the ferrule.

A concavity, a'' , in the bottom of the knob base a' , (see Figs. 2 and 4,) is formed for the purpose of receiving on its surface a covering of gold leaf or other metal or a coat of 105 bright color for the purpose of effecting a conspicuous and showy reflection within the transparent glass knob.

In order to properly protect such thin coating, and also for the purpose of providing a semi-elastic guard and frictional agent between the knob head base and the ferrule 110

material, a disk of very soft metal or of very strong fibrous material, (see Fig. 7,) and as shown in its assigned position by *f* in Fig. 1, is interposed below the knob base, and therefore placed into the bottom of ferrule cup *b'* before the introduction of the knob head base therein.

For the purpose of properly securing such a knob to a lock spindle of round bar shape, 10 such a spindle is entered into aperture *d* to its required depth and position, and hole *e*, Fig. 2, is drilled all through knob and spindle combined, to be permanently held together by pin *e'*, Fig. 1.

15 It is obvious that aperture *d* may be of a different size and shape, according to various makes and shapes of knob spindles, and it may thus be of square shape, or contain a thread for attachment to a threaded 20 spindle, and for such a purpose a set screw of usual size and shape may be contained in the knob hub and used in place of pin *e'*.

Having thus explicitly described my invention and explained its purpose and advantages, I claim—

1. In a door knob a body part rigidly secured within a sheet metal ferrule by frictional contact, said ferrule having a cupped portion engaging the knob head base and

containing teeth embracing and fastening 30 the knob base within said cup portion.

2. In a door knob a sheet metal ferrule having a hub portion containing a body part by frictional contact, and having a cup shaped portion engaging the knob head base, 35 and a row of teeth extending over and clasping the knob base, in combination with a disk of semi-resilient material located between the knob base and the cup bottom.

3. In a door knob a ferrule drawn from 40 sheet metal and having a hub portion inclosing and holding a knob spindle bushing by frictional contact, and a cup portion inclosing and securing the knob head base by teeth on and extending from said cup portion, 45 grooves formed on the knob head base and containing portions of said teeth.

4. In a door knob a sheet metal ferrule having a hub portion, a spindle bushing held therein, and a cupped and toothed portion 50 engaging the knob head base, a concavity in said knob head base containing reflective material, packing material interposed between the knob head base and the ferrule and covering the reflective concavity in said 55 base.

RICHARD A. BREUL.
